UNITED STATES PATENT OFFICE.

OSCAR H. PIEPER AND ALPHONSE F. PIEPER, OF ROCHESTER, NEW YORK.

DENTAL CUSPIDOR-FIXTURE.

1,300,868.

Specification of Letters Patent. Patented Apr. 15, 1919.

Application filed September 8, 1917. Serial No. 190,325.

To all whom it may concern:

Be it known that we, OSCAR H. PIEPER and ALPHONSE F. PIEPER, both of Rochester, in the county of Monroe and State of New York, have invented certain new and useful Improvements in Dental Cuspidor-Fixtures; and we do hereby declare the following to be a full, clear, and exact description of the same, reference being had to the accompanying drawings, forming a part of this specification, and to the reference-numerals thereon.

Our present invention relates to cuspidor fixtures of the class used by dentists, which are intended to be located in proximity to a dental operating chair, and it has for its object to provide an arrangement of parts whereby those auxiliary devices, such as a glass for drinking water, a saliva extractor, and a finger bowl, together with the water supply nozzles for said devices, which it is desirable to locate at one side of the cuspidor, may be adjusted to any desired position about the rim thereof. To this end we have provided an improved mounting for the cuspidor bowl and the aforementioned parts whereby they may be shifted, or rotated, as occasion requires, and locked securely in adjusted position. To these and other ends the invention consists in certain improvements and combinations of parts as will be herein-after more fully described, the novel features being pointed out in the claims at the end of the specification.

35 In the drawings:

Figure 1 is a perspective view of a fixture illustrating one embodiment of our invention in its preferred form;

Fig. 2 is a top plan view showing in full and dotted lines various positions of adjustment of the parts;

Fig. 3 is a central cross-sectional view;

Fig. 4 is a similar view showing a modified arrangement of the auxiliary parts and the adaptation of the drainage supporting arm as an overflow for the cuspidor bowl.

Similar reference characters throughout the drawings indicate similar parts.

In a structure of the character to which our present invention relates it is desirable to have the bowl, which comprises the cuspidor proper, located in a fixed position necessarily adjacent the side of the operating

chair opposite to that occupied by the operator when working upon a patient. Because of the proximity of the cuspidor, which must at all times be within convenient reach of the patient in the dental chair, it occupies a position which occasionally proves inconvenient to the dentist's assistant and often annoying to the operator, especially when the patient toys with the operating valves and appurtenances. This has been found to be especially so since the fixtures comprise devices extending beyond the edge of the cuspidor; such as the usual water glass holder and the saliva ejector, in conjunction with the water nozzles for each, and the usual water supply nozzle for the cuspidor itself. Our present invention, broadly stated, comprises means for mounting the so-called auxiliary devices in such a manner that they are movable in an arc concentric to the edge of the cuspidor bowl, so that when the latter is mounted in the most convenient position with reference to the operating chair, these parts can be adjusted wherever desired in accordance with the wish of the dentist, or operator.

In illustrating the preferred form of our invention we have shown in Figs. 1, 2 and 3, the parts arranged in conjunction with the well known double, or revolving bowl, cuspidor, comprising an outer shell 1, and an inner revolving bowl 2, which is rotated by a jet of water impinging against it from the nozzle 3. The cuspidor may be mounted on any suitable form of support, preferably in the form of a hollow arm 4, which may also comprise a waste pipe for the water, or other fluid escaping from the bowl. The upper end of the support is disposed horizontally, as indicated by 5, and fitted therein is a collar, or coupling member, 6, having an outwardly extending flange 7, beneath which engages a coupling member, or nut 8, having the screw threaded portion shown projecting above the collar 6. Resting upon the latter, and extending upwardly therefrom is a tubular head 9 provided with screw threads at its lower end, coöperating with those of the nut 8, and having at its upper end a socket in which the shell 1 of the bowl is secured by any suitable means, such as the screw threads 10. Extending laterally and upwardly from the head 9 is a tubular arm 11, which pro-

jects to a point opposite the edge of the bowl and supports any desired form of receptacle 12, which in the present instance, is a finger bowl. Within the latter, and extending upwardly therefrom, is the support 13, for holding a water glass, or drinking cup, into which water is delivered by a nozzle 14. The overflow from the holder 13 and the finger bowl 12 passes downwardly within the arm 11 through the head 9, and into the waste pipe leading from the latter.

Another feature of our invention comprehends arranging, in conjunction with the parts described, the fluid, or water pipe connections, which enables them to be made of metal, whereby they move with and readily accommodate themselves to the rotary adjustment of the parts carried on the drainage arm 11. This object we have attained by providing the main water, or fluid supply pipe with a part concentric with the axis movement of the head 9, and carrying them from a movable extension piece supplying the discharge nozzles and which is carried by the arm 11. In carrying out this feature of the invention in its preferred form the main water pipe 15 is concealed within the support 4 and extends to a lug formed interiorly therein which is perforated and virtually comprising a portion of said pipe. Extending downwardly from the latter, and formed on the lower forward side of the support 4 is an extension, or nipple 4^b, the axis of which is in alignment with the axis of rotation of the head 9. If desired a shut-off valve, indicated by 16, may be located above the extension 4^b and engage with the seat formed by the end of the aperture 4^c. Broadly speaking the extension pipe projects from the nipple 4^b, to which it is attached by a pipe union 17, in a direction laterally and upwardly to a point above the cuspidor, and is supported by the drainage arm 11. However, for convenience in construction and assembly, the pipe is made of the double bent piece 18, and the nozzle head 19, the former leading to the union 20, and the latter supported by the union 21, attached respectively to the threaded bosses on the under and upper sides of the arm 11, and between which the connecting pipe 22 extends. The head 19 carries the several valves which control the discharge of water from the various nozzles before mentioned.

It is not essential that the finger bowl discharge directly into the drainage arm, as this may be located to overflow into the cuspidor bowl, or it may be omitted and the drinking glass, or cup, holder employed alone and arranged as shown in Fig. 4, in which the overflow of the cuspidor bowl discharges into the hollow adjustable drainage arm. In this modification a single bowl type of cuspidor is shown, and indicated by

23, having the overflow aperture 24 from which a discharge pipe 25 extends outwardly and downwardly into the upper open end of the drainage arm 11^a, which in this instance terminates close to the periphery of the bowl 23. In this type of fixture the outwardly and upwardly projecting extension of the water pipe 18^a is supported on the drainage arm by means of a tubular boss 26, through which it extends. If desired said pipe may also comprise a nozzle head 27 carrying the cuspidor nozzle 28, the drinking water nozzle 29 and the valves for controlling them. The drinking cup holder 30 is also carried by the head 27 in a plane above the cuspidor bowl and is arranged with its lip 31 overhanging the edge of the bowl.

Another element which usually constitutes one of the auxiliary devices is the saliva extractor, indicated by 32, which is operated by suction produced by the discharge of water from a nozzle 33, discharging into the cuspidor bowl and comprising one of the parts carried on the heads 19 and 27. When the extractor 32 is not in use it is suspended in a suitable clip 34.

It will be seen from the illustrations that the auxiliary devices, in whatever form provided, and irrespective of the type of cuspidor with which they are used, project laterally therefrom and occupy valuable space adjacent the operating dental chair and it is, therefore, highly important that provision be made whereby they may be rotated about the axis of the cuspidor to enable the operator to dispose of them for his greatest convenience and also to swing them to one side or the other so they may not prevent his assistant occupying the most advantageous position adjacent the side of the operating chair where the cuspidor fixture is mounted.

We claim as our invention:

1. In a cuspidor fixture, the combination with a support, a tubular head rotatably adjustable thereon forming a fluid waste, means for locking it in adjusted position, and a cuspidor mounted on the head and discharging therethrough, of a fluid supply pipe having a portion disposed in the axis of the head, an extension rotatable on said portion of the supply pipe, said extension projecting outwardly and upwardly and discharging into the cuspidor, and an arm attached to the head and supporting said extension.

2. In a cuspidor fixture, the combination with a support, a tubular head rotatably adjustable thereon forming a fluid waste and a cuspidor mounted on the head and discharging therethrough, of a fluid supply pipe attached to the support having a downwardly projecting end located in the axis of the head, an extension rotatably connected to said end of the supply pipe and project-

ing therefrom to a point above the cuspidor and a supporting arm projecting from the head and engaging the pipe extension.

3. In a cuspidor fixture, the combination 5 with a hollow support forming a fluid waste, a tubular head rotatable thereon, a cuspidor mounted on the head and discharging therethrough and a fluid supply pipe carried by the support having an extremity projecting 10 downwardly in the axis of said head, of an extension pipe rotatably connected to said extremity of the supply pipe and projecting above and discharging into the cuspidor and an arm carried on the head and supporting 15 the extension pipe.

4. In a cuspidor fixture, the combination with a hollow support forming a fluid waste, a tubular head rotatable thereon, and means 20 for locking it in adjusted position, of a fluid supply pipe carried by the support having a nipple forming an extremity arranged with its axis in that of the tubular head and located beneath the support, a cuspidor mounted on the head and draining therethrough, a 25 pipe extension connected to and rotatable on the nipple and extending therefrom to a point above the cuspidor and an arm on the head projecting laterally beneath the cuspidor supporting the pipe extension at a point 30 removed from its connection with the nipple.

5. In a cuspidor fixture, the combination with a hollow support forming a fluid waste having a horizontally disposed upwardly 35 open end and provided with a downwardly projecting nipple disposed centrally of the opening, a fluid supply pipe leading to the nipple and a tubular head above the open end of the support, of a union coupling for rotatably supporting and locking the head in 40 the desired position of rotary adjustment, a cuspidor carried on said head and draining therethrough, a fluid outlet pipe connected for rotative adjustment to the nipple extending therefrom to a point above the cuspidor 45 and an arm projecting from the head and supporting said pipe.

6. A cuspidor fixture comprising a substantially horizontal hollow support, a second hollow arm journaled to its end and 50 movable in a plane above the same, a cuspidor mounted on the latter concentric with its axis of rotation, a basin carried on the outer end of the movable arm and having draining connections leading thereto, water 55 supply nozzles for the cuspidor and basin supported on said movable arm, and a water supply pipe leading to said nozzles.

7. A cuspidor fixture comprising a substantially horizontal hollow support having 60 an upwardly extending open end, a cuspidor mounted centrally of said opening and draining into the support, a hollow arm journaled on the support and movable about the axis of the cuspidor and communicating with the

interior of said support, a basin carried on 65 the arm and draining thereinto, water nozzles for the basin and the cuspidor supported on the arm, and a water pipe connection leading to said nozzles.

8. A cuspidor fixture comprising a cuspidor having a drainage opening and an outer rim portion concentric therewith, a support for the cuspidor having provision to receive the drainage therefrom, an arm journaled on the support and movable about 70 the axis of the drainage opening, a basin carried on said arm and swinging in an arc about the rim of the cuspidor and fluid nozzles carried by the arm arranged to discharge into the cuspidor and basin.

9. A cuspidor fixture comprising a cuspidor having a drainage opening and an outer rim portion concentric therewith, a hollow member forming a support for the cuspidor about its drainage opening and receiving the waste therefrom, a hollow arm having communication with the interior of the support and extending beyond and adjustable in an arc about the edge of the cuspidor, a basin carried on the extremity of 90 the arm and draining into it and fluid nozzles carried on said arm and discharging into the cuspidor and basin.

10. A cuspidor fixture comprising a circular cuspidor bowl having a central waste 95 fluid outlet, a support for the bowl embodying a hollow member adapted to receive the waste therefrom, a hollow arm journaled on said support, and communicating with the interior thereof, a basin draining into 100 the arm and movable with the latter in an arc concentric with the edge of the bowl, and fluid nozzles carried on the arm and discharging into the bowl and basin.

11. A cuspidor fixture comprising a hollow support having an upwardly opening end, a hollow arm journaled on the support above said opening and communicating therewith, said arm having an aperture in alignment with the opening end of the support, a cuspidor bowl having a drainage opening and fitted on the arm with its opening discharging into the aperture, a basin carried on the outer end of the arm and fluid nozzles mounted on the arm and adapted 110 to discharge into said bowl and basin respectively.

12. In a cuspidor fixture, the combination with a hollow arm forming a fluid waste pipe, a tubular head rotatable thereon, means 115 for locking it in adjusted position, and a cuspidor mounted on the head and draining therethrough, of a fluid supply pipe below the cuspidor, an extension thereon extending outwardly and upwardly above the cuspidor and discharging thereinto and an arm supporting the pipe extension carried on said 120 tubular head.

13. In a cuspidor fixture, the combination with a hollow support having a horizontally disposed open end, a coupling member fitted therein provided with an outwardly projecting flange and a coupling nut journaled on said member beneath the flange and having a threaded portion extending above said member, of a tubular head resting against

the coupling member and having threads co-operating with those of the nut, a cuspidor supported on the head and a tubular drainage arm on the head opening therewith and extending outwardly beyond the edge of the bowl.
